SNOW-MELTING APPARATUS

Lawrence Richardson, Cambridge, Mass.

Application August 24, 1943, Serial No. 499,843

14 Claims. (Cl. 126—343.5)

The present invention relates to snow removal or snow disposal devices and more particularly to a snow melting apparatus adapted to be used to clear streets, highways, railroad right of ways, freight yards, etc.

One of the most common methods of removing snow from streets and highways is to load the same either mechanically or manually upon trucks and then dump the same into a convenient river or sewer opening. On occasions, the snow is first shovelled to one side of the street or highway and is later trucked away. A somewhat similar method of snow removal along railroad tracks includes pushing the snow out of the way to form windrows until the storm ends, then picking it up and loading it, and again unloading it, which necessitates handling the snow three times. Usually two parallel tracks are required, one for the loader and one for the cars, and this requires extra planning and often causes considerable delay in traffic along the tracks. In addition, a considerable number of cars are required for hauling the snow away as well as a great deal of manual help to operate the loader and to shift and unload the cars.

According to the present invention, the snow is preferably mechanically cleared from the streets or railroad right of way by a loader including slats and endless chains and discharged into and immediately melted in a tank containing heated water, the melted snow-water later being dumped into a river or other convenient disposal means when the melting capacity of the apparatus has been reached. Inasmuch as fresh snow weighs about 5 lbs. per cubic foot, it will be apparent that about 12 cubic feet of snow will melt down to about 1 cubic foot of water (about 7½ gallons). Hence, the volume of snow that can be handled by even small tanks is very great. In fact, a device constructed in accordance with the present invention has been operated both efficiently and very satisfactorily.

Other schemes for removing snow have included the use of torches and other sources of flame heat to melt the snow, but these have not proven practicable for the reason that snow itself is a good insulator, and such snow as is melted by the flame runs down beneath the remaining snow and often freezes, forming ice, with the result that conditions are aggravated instead of being improved.

One of the principal advantages of the present invention is that the snow melting apparatus can be put into operation immediately after the storm starts and continue operating throughout the

storm without necessitating pushing of the snow aside and then waiting until the storm ends before picking it up for final disposal. When used in connection with clearing railway tracks, the present invention requires the use of only one track, whereas previously two were required.

The principal object of the invention is to provide a practical snow melting apparatus for use in clearing streets, highways, railroad tracks, etc.

Another object of the invention is to provide a snow melting apparatus which may be operated efficiently and at low cost.

Another object of the invention is to provide snow disposal apparatus in which handling of the snow is reduced to a minimum.

Other objects and advantages will be apparent from the following description taken in conjunction with the accompanying drawings, in which:

20 Figure 1 diagrammatically illustrates one form of the invention adapted to remove snow along a railroad right of way, and shows the relative disposition of a mechanical snow-loading device, a snow-melting car, and a locomotive for moving the loading mechanism and melting car along the track;

Figure 2 is an enlarged plan view of the snow-melting car shown in Figure 1;

30 Figure 3 is a longitudinal sectional view through the snow-melting car taken on the line 3—3 of Figure 2;

Figure 4 is a sectional view through the snow-melting tank or compartment taken on the line 4—4 of Figure 2;

35 Figure 5 is a sectional view through the water-heating tank or compartment taken on the line 5—5 of Figure 2;

40 Figure 6 diagrammatically illustrates a modified snow-melting car including two tanks for heated water and an intermediate tank;

Figure 7 diagrammatically illustrates an embodiment of the invention for removing snow from streets and highways;

45 Figure 8 diagrammatically illustrates a modified, portable snow melting apparatus employing a single tank; and

Figure 9 is a view similar to Figure 8 but showing a further modification of the invention.

50 Referring now to Figure 1 of the drawings, the letter L generally indicates a mechanical snow loading apparatus of any suitable or conventional construction. The snow loading device L is connected by a coupling 1 to a snow melting car generally indicated by the numeral 2, which in turn is coupled at 3 to a locomotive 4.

The car 2 comprises a snow receiving tank or compartment 5 and a water tank or compartment 6 adapted to contain heated water. The tanks or compartments 5 and 6 are preferably arranged end to end or adjacent to each other and communicate through openings 7 controlled by manually operated lift valves 8. The valves 8 are of the disc type and are pivotally connected to a lever 9 fulcrumed about a pin 10. A link 11 is connected at its lower end to the free end of the lever 9 and its upper end is connected to a manually operable lever 12 arranged above the top 13 of the water tank 6.

A steam line 15, extending longitudinally along one side of the car 2 above the tanks 5 and 6, is connected at one end by a flexible tube 16 with a pipe 17 communicating with the steam boiler of the locomotive 4. A branch pipe 18 extends laterally from the line 15 above the tank 6 and in turn is connected with a pipe line 19 containing two globe type valves 20, which are manually operable through stem extensions 21. The pipe line 19 includes a vertical depending pipe 22 disposed on the discharge side of each of the valves 20 and a horizontal perforated pipe 23 connected with the lower end of the pipe 22 and extending longitudinally of the water tank. The perforated pipes 23 are arranged adjacent the bottom wall 24 of the water tank 6 upon the opposite sides of a longitudinal baffle plate B. The top wall 13 of the water tank 6 has a generally oval-shaped opening 25 through which water may be conveniently introduced from any suitable source (for example, through an injector, not shown, on the car 2) at the time that the snow-melting device is initially put into operation. Upon opening one or both of the valves 20, steam will be introduced into the water in the tank 6 through the perforated pipes 23 to agitate and heat said water to any temperature desired. The agitation of the water results in uniform heating thereof so that there are no localized cold and hot zones.

The loading device L includes a wide, endless conveyor 30 which picks up the snow along the track and discharges the same onto an inclined apron 31. The lower end of the apron 31 is arranged so that the snow deposited thereon will be discharged through an opening 32 in the top wall 33 of the snow-melting tank 5. The top wall 33 is inclined downwardly at its rear end, as indicated at 34, and terminates in a horizontal portion 35 upon which is constructed a wooden platform 36 for the operator. It will be noted that the platform 36 is located so that the valve control handles 12 and 21 are within convenient reach.

A vertical screen 37 is mounted in the melting tank 5 at a point between the inclined wall 34 and the bottom wall 33 of said tank. This screen will prevent the passage from the melting tank 5 into the water tank 6 of any debris that may be picked up with the snow. Hollow columns 39 extend through both tanks 5 and 6 and serve as drains for any water collected upon the top walls of said tanks.

When the apparatus is in use, and after the water in the water tank 6 has been heated to the desired temperature, the levers 12 are operated to effect opening of the valves 8. Heated water will then pass through the openings 7 from the water tank 6 into the melting tank 5. The valves 8 are held open until the water reaches a common level in the tanks 5 and 6. When the water is released from the water tank 6 into the melting tank 5, both will be about half full. However,

as snow is fed through the opening 32 into the melting tank 5, it will be melted by the heated water and the level will rise in both tanks. The valves 8 are such that they will automatically permit the water to back-up into the water tank 6. The loading and melting operation is continued until sufficient snow has been melted to substantially fill both tanks 5 and 6. The car 2 is then pulled onto a bridge or any other suitable location to effect dumping of the water from the melting tank 5. Emptying of the tank 5 is effected through a plurality of lift valves 40, similar to the valves 8, arranged along the opposite sides of the car 2 near the bottom of the melting tank 5, as is best shown in Figs. 1, 3 and 4. Meanwhile, the valves 8 will automatically remain closed as the liquid level drops in the melting tank 5 so that draining of the melting tank 5 occurs without draining water tank 6.

While the car 2 is being hauled to or from a suitable dumping place, the valves 20 may be opened to admit steam to heat and agitate the water contained in the water tank 6 for the next melting cycle. The heating of the water in the tank 6 is preferably so controlled that when the device is in use and the snow-melting tank 5 has become filled, the temperature of the water in both tanks will be about 32° F., or slightly thereabove. This results in a maximum of heat efficiency.

It may be desirable in certain instances to also heat the water flooded over into the melting tank 5 from the tank 6. For example, it may be desirable to add some heat to the water in tank 5 to hasten the snow melting operation or to keep it from freezing until it is dumped. To this end, the pipe line 15 is extended to the melting tank 5. This line contains a valve 41 which controls the flow of steam to a series of ejectors in the tank 5. Thus, the line 15 includes a pipe 42 (Figures 3 and 4) extending into the tank 5 connected with a pair of ejectors 43 disposed adjacent the bottom 33 of said tank. The ejectors 43 are vented to the atmosphere through tubes 44 extending through the top wall 33. Another pair of ejectors 45 is positioned about midway of the height of the tank 5 and connected with a pipe 46 which, in turn, is connected with the steam line 15, as indicated at 47 in Fig. 2. A valve 48 controls the flow of steam to the ejectors 45. Vent tubes 49 extend through the top wall 33 of the tank 5 for venting said ejectors 45 to the atmosphere. The steam introduced through the ejectors 43 and 45 heats and agitates the water present in the tank 5 at different levels and causes circulation thereof assuring substantially uniform heating to any degree desired.

While the locomotive 4 has been described as the means for providing steam for heating water in the tanks 5 and 6, it will be understood that any suitable auxiliary apparatus may be used in lieu of the locomotive for heating the water, such as an oil burning apparatus X shown in dot-and-dash lines in Figure 3.

Referring now to the modified melting car shown in Figure 6, the car 2a here illustrated includes a snow melting compartment 5a and two water compartments 6a and 6b, one at each end of the car. Steam for heating the water in the compartments 6a and 6b is provided by a line 15a connected with suitable ejectors 50a and 50b in the tanks 6a and 6b, respectively. The steam to the ejectors 50a and 50b is separately controlled by valves 51 and 52, respectively. An ejector 53 is located in the melting tank 5a and is

controlled by a valve 54. One or more valves 8a control the communication between the water tank 6a and the melting tank 5a, and valves 8b control communication between the melting tank 5a and the water tank 6b. A dump valve 48a controls the dumping of melted snow-water from the tank 5a. Of course, the tank 5a is provided with an inlet opening 32a for the snow to be melted.

The operation of the device shown in Figure 6 is substantially the same as that of the apparatus shown in Figures 1 and 5. However, in starting the operation, both heating compartments 6a and 6b are preferably filled with water. After the water in the tank 6a has been heated, the valve 8a is opened, and the hot water flows into the melting tank 5a, the water level in the tanks 6a and 5a equalizing. The valve 51 is then opened to heat the water in the other water tank 6b. Snow is elevated and dumped (as previously described) through the opening 32a into the melting tank 5a, where it is melted by the hot water. This melted snow raises the water level in tank 5a and part of the water flows back through the valve 8a into the water tank 6a, the levels in the two tanks maintaining equality as the level rises. If the water in the tank 5a gets too cold to melt the snow rapidly, additional steam may be added thereto by opening the valve 54, whereupon steam is introduced directly into the water in said tank to heat the same. This operation of melting the snow continues until tanks 5a and 6a are full. The car 2a is then moved to a convenient place and the snow-water is dumped from the melting compartment 5a through the valve 49a in the bottom thereof. The valve 8a stays closed so that the tank 5a remains full. Meanwhile, the water in the tank 6b has been heated, and when the car 2a has been returned to its site of operation, the valve 8b is opened, flooding the tank 5a, and the cycle is repeated. Thus, by using two heating tanks 6a and 6b, and alternating the use of the water from these tanks with the melting tank 5a, the speed of operation and capacity of the melting car is increased.

Figure 7 diagrammatically illustrates the adaptation of the present invention for use in removing snow from streets and highways. In this figure, the numeral 69 generally identifies a snow loading apparatus including an endless conveyor 61 which discharges onto an apron 62 positioned above an opening 63 in a melting tank 64 mounted on a self-propelled truck 65. The truck 65 includes a water tank 66 adapted to contain heated water that may be flooded into the melting tank 64 by opening a valve 67 arranged adjacent a partition 68 between the tanks 64 and 66. The water in the tank 66 is heated by an oil burner or equivalent apparatus 69 conveniently mounted upon the truck 65. A screen 70 prevents any debris picked up with the snow from being carried from the melting tank 64 into the water tank 66 as the level rises in the tanks due to the melting of the snow dumped into the tank 64. A drain valve 71 mounted upon the melting tank 64 serves as a means to drain said melting tank.

A pipe line 72 running from the heating device 69 is connected by a pipe 73 for heating the water in tank 66 and a valve 74 controls the flow of the heating medium through said pipe. Similarly, a pipe 75 containing a valve 76 is connected with the line 72 for furnishing supplemental heat to the melting tank 64. After the tank 66 has been initially filled the heating device 69 may draw water therefrom through a pipe 77, to make a self-contained snow-melting unit.

The operation of the device shown in Figure 7 is the same as that shown in Figure 1. That is to say, hot water from the tank 66 is flooded into the melting tank 64 by opening the valve 67. Snow dumped into the melting tank 64 is melted by the hot water and as the level rises the water will back up into the tank 66 so that both tanks are filled. Whereupon, the truck 65 will be moved away from the loader 60 and the valve 70 later opened to drain the water from the melting tank at a convenient point of disposal, such as a sewer manhole. Meanwhile the water in the tank 66 is heated for the next melting cycle.

Referring now to Figure 8, a snow melting apparatus is disclosed employing a single tank which serves both as a water tank and as a melting tank. Thus, the tank 80 is provided with a pair of dump valves 81 which are located at a point approximately midway of the height of said tank. Hence, when the dump valves 81 are actuated only the water above the level of the dump valves 81 will drain from the tank 80 and the tank will therefore normally be half full of water. This water is heated by steam ejectors 82 to prepare the same for the next melting cycle. A drain valve 83 is connected with the bottom of the tank 80 to effect complete draining of said tank when desired.

The operation of the single tank shown in Figure 8 is generally the same as that of the two and three tank constructions described hereinbefore. It will be understood that snow is introduced into the tank 80 through a suitable opening 84 and the snow thus introduced is melted by the heated water in said tank. When sufficient snow has been introduced into the tank 80 and melted so that said tank is full of water, the vehicle 85 carrying said tank may then be moved to a convenient place for dumping the water by opening of the valves 81. Only half of the water will be drained from the tank 80 as previously pointed out, and the water remaining in said tank may be heated by the ejectors 82 as the vehicle 85 is being returned to its working location.

Figure 9 illustrates a modification of the single tank construction in which a tank 86 is provided with one or more dump valves 87 located adjacent the bottom thereof so that said tank is substantially completely drained when said dump valves are opened. In the operation of this particular form of the invention, hot water may be introduced into the tank 86 through a pipe 88 which has a horizontally extending perforated portion 89 disposed adjacent the bottom of said tank. The hot water may be introduced into the tank 86 to partially fill the same before placing the tank in operation, or heated water (or steam) may be introduced into the tank to melt the snow as the snow is deposited therein. After the tank 86 is partially filled, only enough hot water or steam is added to the liquid in said tank to melt such additional snow as may be required to completely fill the tank 86 with water. This results in very economical operation because no excess heat is provided which goes to waste. When the tank 86 is full, the vehicle 90 is moved to a suitable point for draining by opening the valve (or valves) 87.

It will be understood that various changes may be made in the arrangement and number of tanks and in the details of the valves disclosed herein and in the heating means employed for heating the water in the tanks, without departing from the spirit of the invention or the scope of the annexed claims.

I claim:

1. Snow disposal apparatus comprising: a tank adapted to contain heated water; a second tank adapted to receive snow to be melted; means including a semi-automatic valve establishing communication between said tanks and controlling the flow of water between said tanks arranged so that heated water from said water tank can be admitted into said melting tank under manual control for melting snow introduced thereto, and melted snow-water can automatically flow back into said water tank until both said tanks are substantially full; and a manually operable drain valve connected with said melting tank for draining said melting tank when said semi-automatic flow control valve is closed without draining said water tank.

2. Snow disposal apparatus comprising: a first tank adapted to contain heated water; a second tank adapted to receive snow to be melted; means establishing intercommunication and controlling the flow of water between said tanks arranged so that heated water from said water tank can be admitted into said melting tank for melting snow introduced thereto, and melted snow-water can flow back into said first tank until both said tanks are substantially full; means for supplying supplemental heat to said melting tank for supplementing the heat of the original heated water and to heat the melted-snow water; and means for draining said melting tank.

3. Snow melting apparatus comprising: a first tank adapted to contain heated water; means including an element in said tank for heating the water in said tank; a second tank adapted to receive snow to be melted; means establishing intercommunication and controlling the flow of water between said tanks arranged so that heated water from said water tank can be admitted into said melting tank for melting snow introduced thereto, and melted snow water can flow back into said water tank until both said tanks are substantially full; means for supplying supplemental heat to said melting tank for supplementing the heat of the original heated water and to heat the melted snow-water; and means for draining said melting tank when said flow control means is closed without draining said water tank.

4. Snow disposal apparatus comprising: a first tank adapted to contain heated water; a second tank adapted to receive snow to be melted; means establishing intercommunication and controlling the flow of water between said tanks arranged so that heated water from said water tank can be admitted into said melting tank for melting snow introduced thereto, and melted snow-water can flow back into said water tank until both said tanks are substantially full; a screen for preventing any debris introduced with said snow from being carried into said water tank; and drain means on said melting tank for draining said melting tank when said flow control means is closed without draining said water tank.

5. Snow disposal apparatus comprising: a first tank adapted to contain heated water; means including an element in said tank for heating the water in said tank; a second tank adapted to receive snow to be melted; means establishing intercommunication and controlling the flow of water between said tanks arranged so that heated water from said water tank can be admitted into said melting tank for melting snow introduced thereto and melted snow-water can flow back into said water tank until both said tanks are substantially full; a screen

in said melting tank for preventing any debris introduced with said snow from being carried into said water tank; and a drain valve at one side of said melting tank for draining said melting tank when said flow control means is closed without draining said water tank.

6. Snow disposal apparatus comprising: three tanks, two of said tanks being adapted to contain heated water and the other being adapted to receive snow to be melted; means establishing intercommunication and controlling the flow of water between each of said water tanks and said melting tank arranged so that heated water from said water tanks can be alternately admitted into said melting tank for melting snow introduced thereto, and melted snow water can flow back into a given one of said water tanks until both said given water tank and said melting tank are substantially full; and means for draining said melting tank.

7. Snow disposal apparatus comprising: a pair of water-heating tanks and a snow-melting tank intermediate said water-heating tanks; means establishing intercommunication and controlling flow between each of said water-heating tanks and said snow-melting tank arranged so that the heated water from either one of said water-heating tanks may be flooded into said snow-melting tank to melt the snow introduced thereto; means for draining said snow-melting tank; and means for heating the water contained in either of said water-heating tanks while said snow-melting tank is draining.

8. Snow disposal apparatus comprising: a railway car; a pair of tanks carried by said car adapted to be filled with water; means in each of said tanks for heating said water; a steam line extending longitudinally of said railway car; piping including a valve connecting each of said heating means with said steam line, whereby steam may be introduced into the water in said tanks to heat said water; a third tank carried by said car adapted to receive snow to be melted; means for placing said tanks in communication including valve means for controlling the flow between each of said pair of tanks and said third tank, whereby upon opening of said valve means the heated water from either one of said pair of tanks can be flooded into said third tank to melt the snow introduced thereto; and drain valve means on said third tank for draining said third tank when said flow control valve means is closed without draining either of said tanks of said pair of tanks.

9. Snow disposal apparatus comprising: a railway car; a pair of tanks carried by said car adapted to be filled with water; means in each of said tanks for heating said water; a steam line extending longitudinally of said railway car; piping including a valve connecting each of said heating means with said steam line whereby steam may be introduced into the water in said tanks to heat said water; a third tank carried by said car adapted to receive snow to be melted; means for placing said tanks in communication including valve means for controlling the flow between each of said pair of tanks and said third tank arranged so that the heated water from either one of said pair of tanks can be flooded into said third tank to melt the snow introduced thereto; heating means in said third tank for supplying supplemental heat to the original heated water and melted snow-water; piping including a valve connecting said steam line with said last-mentioned heating means; and drain

valve means connected with said third tank for draining said third tank when said flow control valve means is closed without draining either of said tanks of said pair of tanks.

10. Snow melting apparatus comprising: a first tank adapted to contain heated water; a second tank adapted to receive snow to be melted, said tanks intercommunicating through an opening; a check valve arranged to control the flow through said opening, said check valve being manually operable to permit the flow of heated water from said water tank into said melting tank for melting snow introduced thereinto, said check valve being automatically operable to permit melted snow-water to flow back into said water tank as the level in the melting tank exceeds that in said water tank; and means for draining said melting tank, said check valve preventing draining of said water tank while said melting tank is being drained.

11. Snow disposal apparatus comprising: three tanks, two of said tanks being adapted to contain heated water and the other being adapted to receive snow to be melted, each of said water tanks communicating with said melting tank through an opening; a check valve arranged to control the flow through each of said openings, said check valves being selectively manually operable to permit the flow of heated water from either of said water tanks into said melting tank for melting snow introduced thereinto, said check valves being automatically operable to permit melted snow-water to flow back into either of said water tanks as the level in the melting tank exceeds that in either of said water tanks; and means for draining said melting tank.

12. Snow disposal apparatus comprising: a railway car; a pair of tanks carried by said car adapted to be filled with water; means in each of said tanks for heating said water; a steam line extending longitudinally of said railway car; piping including a valve connecting each of said heating means with said steam line, whereby steam may be introduced into the water in said

tanks to heat said water; a third tank carried by said car adapted to receive snow to be melted, each of said water tanks communicating with said melting tank through an opening; a check valve arranged to control the flow through each of said openings, said check valves being selectively manually operable to permit the flow of heated water from either of said water tanks into said melting tank for melting snow introduced thereinto, said check valves being automatically operable to permit melted snow-water to flow back into either of said water tanks as the level in the melting tank exceeds that in either of said water tanks; and means for draining said melting tank.

13. Snow melting apparatus comprising: a first tank adapted to contain heated water; a second tank adapted to receive snow to be melted; means establishing and controlling intercommunication between said tanks arranged so that heated water from said water tank can be admitted into said melting tank under manual control for melting snow introduced thereinto, and melted snow-water can automatically flow back into said water tank as the level in said melting tank rises above the level in said water tank; and means for draining said melting tank.

14. Snow disposal apparatus comprising: a first tank adapted to contain heated water; means including an element in said tank for heating the water in said tank; a second tank adapted to receive snow to be melted; means establishing intercommunication and controlling the flow of water between said tanks arranged so that heated water from said water tank can be admitted into said melting tank under manual control for melting snow introduced thereinto, and melted snow-water can automatically flow back into said water tank as the level in said melting tank rises above the level in said water tank; and draining means for draining said melting tank.

LAWRENCE RICHARDSON.
